US00D891423S

(12) **United States Design Patent** (10) **Patent No.:** **US D891,423 S**
(45) **Date of Patent:** **** Jul. 28, 2020**

(54) **NOTEBOOK COMPUTER**

(71) Applicant: **SAMSUNG ELECTRONICS CO., LTD.**, Suwon-si, Gyeonggi-do (KR)

(72) Inventors: **Hoyoung Seoc**, Seoul (KR); **Dongseok Lee**, Seoul (KR); **Iksang Kim**, Seoul (KR)

(73) Assignee: **SAMSUNG ELECTRONICS CO., LTD.**, Gyeonggi-Do (KR)

(**) Term: **15 Years**

(21) Appl. No.: **29/644,389**

(22) Filed: **Apr. 17, 2018**

(30) **Foreign Application Priority Data**

Nov. 3, 2017 (KR) 30-2017-0051341

(51) **LOC (12) Cl.** **14-02**

(52) **U.S. Cl.**

USPC **D14/327**

(57) **CLAIM**

The ornamental design for a notebook computer, as shown and described.

DESCRIPTION

FIG. 1 is a top rear perspective view of a notebook computer showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a bottom perspective view thereof; and,

FIG. 9 is another top view thereof showing an unfolded state of the notebook computer.

The broken lines illustrating portions of the notebook computer form no part of the claimed design.

1 Claim, 5 Drawing Sheets
